UNITED STATES PATENT OFFICE

166,092

SPORT SHIRT

Jesse D. McDonald, Enid, Okla.

Application November 9, 1951, Serial No. 17,342

Term of patent 14 years

(Cl. D3—25)

To all whom it may concern:

Be it known that I, Jesse D. McDonald, a citizen of the United States, residing at Enid, State of Oklahoma, have invented a new, original, and ornamental Design for a Sport Shirt, of which the following is a specification, reference being had to the accompanying drawing, forming a part hereof.

Fig. 1 is a front view of a sport shirt showing my new design, the collar being in its closed position.

Fig. 2 is a rear view.

Fig. 3 is another front view of that shown in Fig. 1 showing the collar in open position and with the necktie holding tab removed.

I claim:

The ornamental design for a sport shirt, as shown and described.

JESSE D. McDONALD.
